IGNITION DISTRIBUTOR FOR INTERNAL COMBUSTION ENGINES

Wilhelm Walther, Stuttgart, Germany, assignor
to Robert Bosch Aktiengesellschaft, Stuttgart,
Germany

Application October 5, 1932, Serial No. 636,401
In Germany October 13, 1931

5 Claims. (Cl. 200—19)

The present invention relates to ignition distributors for internal combustion engines and more particularly to means for securing a protective cap and the distributor disc to the casing of 5 the distributor.

The object of the present invention is to produce a cheap arrangement, which is applicable both for the joint fastening of the distributor disc and protective cap, as well as for the fastening of the distributor disc alone in the absence 10 of the protective cap. This is attained, according to the present invention in that the distributor disc is provided with projections which support the protective cover and bear upon the distributor casing, the protective cap being secured to the casing by holding means so that the projections are nipped between the cap and the casing and the distributor disc thus secured in position.

20 An example of construction of the invention is shown in the drawings, in which:

Fig. 1 shows the distributor, partly in section,

Fig. 2 is a section of a part of the top of the distributor on the line A—A of Fig. 1,

25 Fig. 3 is a side elevation,

Fig. 4 is a plan view and

Fig. 5 is a view of a part of the distributor.

A distributor shaft 3 is mounted in a neck-bearing 1, which is enlarged above to form a casing 2 for an interrupter, and the distributor shaft carries in the usual way an interrupter cam 4 and a rotary distributor piece 5. A distributor disc 6 is mounted on the rim of the casing 2 of the interrupter by means of a metal flange 7 moulded in the distributor disc which consists of 30 insulating material. On the flange 7 is seated a protective cap of metal, consisting of two halves 8 and 9. The half 8 is seated on the flange 7, and the half 9 on the half 8.

40 The two halves of the protective cap are held together by two swing-bolts 10, and together with the distributor disc, on the flange of which the protective cap is mounted, pressed on the casing 2. The swing-bolts are mounted by means of 45 pins 11 in slots 12 of two lugs 13 on the casing 2. On the upper half 9 of the protective cap 2 are cast two eyes 14 having slots 15 in which the bolts 10 can be inserted and tightened by means of nuts 16. The flange 7 of the distributor disc has

50 in its turn also two lugs 16 having recesses 17 (Fig. 5). The distributor disc 6 is so mounted on the casing 2 that the lugs 16 of the flange lie above the bearing lugs 13 for the swing-bolts, so that these latter can pass through the recesses

55 17. The lugs 16 are for the purpose of being able to fasten the distributor disc on the casing 2 even without the protective cap. The swing-bolts are in this case made correspondingly shorter.

The protective cap is to serve not only for protection against material injury or against dirt

and moisture, but also for screening electromagnetic waves proceeding from the current-carrying parts of the distributor disc. For this reason the flange 7 must be of metal, so that the metal protective cap has a metallic connection 65 with the earthed casing 2.

I declare that what I claim is:

1. An ignition distributor for internal combustion engines comprising a casing, a metallic protective and electrical shielding cap for said casing, a distributor disc, a rotary distributor piece mounted in said casing, said distributor disc being provided with metallic projections supporting said protective cap and engaging said casing to provide an electrical connection between said cap 75 and casing, and means for securing said cap and said disc to said casing.

2. An ignition distributor for internal combustion engines comprising a casing, a protective cap for said casing, a distributor disc, a rotary distributor piece mounted in said casing, a metal flange moulded in said distributor disc, engaging said casing and forming a bearing surface for said protective cap, and holding means secured on said casing and engaging said protective cap 85 to urge it onto said flange.

3. An ignition distributor for internal combustion engines comprising a casing, a protective cap for said casing divided circumferentially to form two parts, a distributor disc, a rotary distributor piece mounted in said casing, projections on said distributor disc supporting said protective cap and engaging said casing, and holding means secured on said casing and engaging said protective cap to urge it onto said projections. 95

4. An ignition distributor for internal combustion engines comprising a casing, a protective cap for said casing having at least two recessed ears thereon, a distributor disc, a rotary distributor piece mounted in said casing, a metal flange moulded in said distributor disc to form a bearing surface for said protective cap and at least two swing bolts revolubly mounted on said casing and engaging the recessed ears in said protective cap to urge said cap onto said flange and said flange 100 onto said casing.

5. An ignition distributor for internal combustion engines comprising a casing, a metallic protective and electrical shielding cap for said casing having at least two recessed ears thereon, a distributor disc, a rotating distributor piece, an annular metal flange secured to said distributor disc to form a bearing surface for said protective cap and an electrical connection between said cap and casing, at least two recessed projections on 110 said flange and at least two swing-bolts revolubly mounted on said casing and engaging in the said recessed projections and in the recessed ears on the protective cap. 115

WILHELM WALTER. 120
